UNITED STATES PATENT OFFICE

148,905

DESIGN FOR A COMBINATION LAMP AND
POTTED PLANT BOWL

Robert O. Bextel, Chicago, Ill.

Application April 19, 1947, Serial No. 138,492

Term of patent 14 years

(Cl. D48—20)

To all whom it may concern:

Be it known that I, Robert O. Bextel, a citizen of the United States and a resident of Chicago, in the county of Cook and State of Illinois, have invented a new, original, and ornamental Design for a Combination Lamp and Potted Plant Bowl, of which the following is a specification, reference being had to the accompanying drawing, forming a part thereof, in which:

Figure 1 is a side view of the combination lamp and potted plant bowl showing my new design;

Figure 2 is a view taken on line 2—2 of Figure 1; and

Figure 3 is a vertical sectional view of the right half of the main portion of the lamp.

The characteristic features of my design reside in the portions shown in full lines.

I claim:

The ornamental design for a combination lamp and potted plant bowl, as shown and described.

ROBERT O. BEXTEL.
